CLAIM

The ornamental design for a tactical belt comprising a mounting matrix, as shown and described.

DESCRIPTION

FIG. 1 is a front perspective view of a new design for a tactical belt comprising a mounting matrix.

FIG. 2 is a front plan view of a new design for a tactical belt comprising a mounting matrix.

FIG. 3 is a back plan view of a new design for a tactical belt comprising a mounting matrix.

FIG. 4 is a right side view of a new design for a tactical belt comprising a mounting matrix.

FIG. 5 is a left side view of a new design for a tactical belt comprising a mounting matrix.

FIG. 6 is a top view of a new design for a tactical belt comprising a mounting matrix; and,

FIG. 7 is a bottom view of a new design for a tactical belt comprising a mounting matrix.

The regularly broken lines of the drawings show portions of the article that form no part of the claimed design. The dot-dash line indicates stitching between the panels of the tactical belt comprising a mounting matrix that does not form part of the claim. The tactical belt comprising a mounting matrix is shown with a symbolic break in its length represented by dot-dot-dash broken lines forming no part of the claim. The appearance of any portion of the article between the break lines forms no part of the claimed design.
